UNITED STATES PATENT OFFICE.

HARRY H. HARGRAVE, OF LONG BEACH, CALIFORNIA.

SLIDE MAT.

Application filed October 8, 1925. Serial No. 61,202.

This invention relates to mats of the type employed for supporting a person while traveling down an amusement slide, and an object of the invention is to provide a construction that will insure against the person falling off of the mat, and that will prevent the skirts of women passengers from billowing.

Some amusement slides are built with curves in them, and thus the person traveling down the slide tends to be thrown by centrifugal force to the outer wall of the slide at the curves. Accordingly, an important object of this invention is to protect the person from contact with the side walls of the slide.

Another object is to cause the mat to tend to slide toward the inner wall on curves so as to avoid excessive friction between the outer wall and the adjacent side wall of the mat.

A very important object is to provide a mat that can be used with equal success whether the slide by dry or damp. Since slides are constructed largely at beach resorts, it will be readily understood that the prevalent mists or fogs dampen the slides and that, accordingly, the coefficient of friction between the mat and the slide is a variable. To properly take care of this difference in friction, the mat is so constructed that the under surface thereof can be readily provided with a wooden runner or runners.

Another object is to provide a construction in which the runner is in such position as to receive most of the weight of the person on the mat, thus minimizing pressure of the fiber floor of the mat upon the slide so that the mat will travel faster down the slide than if the weight were largely upon the fiber floor.

Another object is to facilitate manufacture of the mat floor by utilizing the fiber in the form of rope.

Other objects and advantages will appear from the subjoined detailed description.

The accompanying drawings illustrate the invention:

Fig. 1 is a plan view of the slide mat constructed in accordance with the provisions of this invention, a portion of the floor being broken away.

Fig. 2 is a front elevation of Fig. 1.

Fig. 3 is a sectional elevation on the line indicated by 3—3, Fig. 1.

Fig. 4 is an enlarged fragmental plan view of the floor of the mat.

Fig. 5 is an enlarged sectional detail on the line indicated by 5—5, Fig. 1.

The floor of the mat is indicated at 6 and is of fiber. For example, the floor may be of cocoanut fiber or any other fibrous material highly resistant to wear and having a low frictional value. In the instance shown, more particularly in Fig. 4, the fiber is in rope form, the rope being led back and forth to form a substantially rectangular perforate body 7 and said rectangular body being encircled or surrounded by inner and outer rope members 8, 9, respectively. In this instance, the rope body 7 is partly formed by a series of parallel rows of loops 10, said loops being formed by transverse passes of the rope to and fro, and said body also includes straight rope members 11 which are interposed between adjacent rows of loops. The members 11 and loops 10 are secured together by stitches 12 or other suitable fastening means. Stitches 13 secure the outermost loops 10 to the inner encircling rope member 8. The stitches 12, 13 preferably pass horizontally through the rope and over the rope and are not exposed at the under surface of the floor. Secured to the inner encircling member 8 by stitches 14, or other suitable means, are fabric side walls 15 and a fabric front wall 16. The walls 15, 16 may be made of canvas and may join one another as shown. Preferably the walls 15, 16 are joined together in such manner as to cause them to extend inwardly and upwardly, thus to constrict the opening 17 between the upper margins of the walls. In other words, the combined lengths of the upper margins of the walls are less than the combined lengths of the lower margins of the walls.

The fabric, of which the walls 15, 16 are constructed, is provided at its upper margin with a hem forming a pocket 18 provided with openings 19 along the side walls 15, and a rope member 20 lies partially within the pocket 18 and has portions 20 protruding through the openings 19 to form hand holds or grips so that the passenger may hold the walls 15 elevated to properly protect him from the walls of the slide down which the mat is moving, and to insure against his falling off of the mat. The walls 15, 16 may be closed down upon the skirt of a woman seated in the forward portion of the mat, so as to prevent the air from billowing the skirt.

It will be understood that to use the mat described above, such mat will be placed on a level support at the upper end of the slide and a person or persons will seat themselves

on the floor of the mat and close the walls 15, 16 around them. The passengers will preferably place their arms on the inner sides of the walls 15 so as to properly protect them 5 against the walls of the slide. The mat will then be pushed off of the support or the support will be tilted to cause the mat to move onto the inclined surface of the slide in a manner understood by those skilled in the 10 art relating to amusement slides.

When slides become damp from dew, fog or rain, so much friction would be produced between the mat fiber and the floor of the slide that the mats would not travel down the 15 slide at the desired rate of speed. Accordingly, I have provided runners 21 of wood, which may be secured to the under face of the floor in such position that the weight of the passenger or passengers will be sustained principally upon the runner or runners. The runners 21 are secured to the floor of the mat by any suitable means, the construction I prefer 20 at present being as follows:—The runners 21 are provided with transversely extending 25 holes 22 through which extend flexible members or thongs 23 of leather or other suitable material. The end portions of the thongs 23 pass through perforations of the mat floor and are tied or otherwise secured, as indicated at 24, at the upper face of the mat floor.

As mentioned above, the slides frequently have curves in them, many being built in the form of a spiral so that one of the walls of the slide is always the outer wall. It may be 35 assumed, for example, that the curves are constructed so that the outer walls of the curved portions are on the right of the person traveling down the slide. In traveling around such curved portions, there is, of course, a tendency for the mat and its occupant to be thrown by centrifugal force to the 40 right against the outer wall of the curve. To minimize this tendency, the runners 21 are preferably placed diagonally with respect to 45 the longitudinal axis of the mat, the runners being aslant forwardly away from that edge of the mat that is adjacent to the outer wall of the curve of the slide down which the mat travels. This causes the mat to tend to run 50 inwardly away from the outer wall of the curve and so relieve the pressure of the mat against the outer wall, thus avoiding excessive friction between the outer wall and the adjacent side of the mat. This insures the 55 passengers against injury by frictional heat

or otherwise in event of their arms or other portions of their bodies being exposed.

I claim:—

1. A slide mat comprising a fiber floor, and fabric walls secured to the marginal portion of the floor and extending inwardly and upwardly so as to constrict the opening between the upper margins of said walls. 60

2. A slide mat comprising a fiber floor, fabric walls secured to the floor along the side margins and one end margin of the floor, the combined lengths of the upper margins of the walls being less than the combined lengths of the lower margins of said walls, and grips on the upper margins of the side walls. 65

3. A slide mat comprising a fiber floor, fabric walls secured to the floor along the side margins and one end margin of the floor, the fabric having a pocket at its upper margin with openings therein along the side walls, 70 and a rope member partly in the pocket and protruding through the openings to form grips.

4. A slide mat comprising a substantially rectangular floor body of fiber, inner and outer rope members encircling the body, and side walls of fabric secured to the inner encircling rope member. 80

5. A slide mat comprising a substantially rectangular floor body of fiber, a rope member 85 encircling said body, and an end wall and side walls secured to the encircling rope member and joined together, the combined lengths of the upper margins of the walls being less than the combined lengths of the lower margins of the walls. 90

6. A slide mat comprising a substantially rectangular floor body of fiber, and a wooden runner secured to the floor body on the under-face thereof. 95

7. A slide mat comprising a substantially rectangular floor body of fiber, and a wooden runner secured to the floor body on the under-face thereof, said runner being aslant to the longitudinal axis of the floor body. 100

8. A slide mat comprising a substantially rectangular floor body of fiber, a wooden runner having transversely extending holes therethrough, and thongs passing through the holes and through the floor body, the end portions of each of said thongs being secured together at the upper face of the floor body. 105

Signed at Los Angeles, Calif., this 30 day of Sept., 1925.
